COMBINED CAN AND BOTTLE OPENER OR THE LIKE

Walter W. Edlund, Burlington, Vt.

Application November 4, 1953, Serial No. 27,449

Term of patent 7 years

(Cl. D44—29)

To all whom it may concern:

Be it known that I, Walter W. Edlund, a citizen of the United States, residing at Burlington, in the State of Vermont, have invented a new, original and ornamental Design for a Combined Can and Bottle Opener or the like, of which the following is a specification, reference being had to the accompanying drawing, forming a part thereof.

Figure 1 is a perspective view of the combined can and bottle opener embodying my new design,

Figure 2 is a front elevational view thereof with a portion broken away for convenience of illustration, and,

Figure 3 is a fragmentary rear elevational view thereof.

I claim:

The ornamental design for a combined can and bottle opener or the like, as shown and described.
